UNITED STATES PATENT OFFICE

2,018,672

SURGE DIVERTER

Leland H. Hill, Wauwatosa, Wis., assignor to Allis-Chalmers Manufacturing Company, Milwaukee, Wis., a corporation of Delaware

Application March 13, 1933, Serial No. 660,487

9 Claims. (Cl. 175—30)

This invention relates in general to devices for preventing the flow of high voltage surge currents into electrical apparatus such as transformers, reactors, circuit breakers, and the like; and relates more particularly to surge diverters which may be mechanically attached to apparatus of the above type in such a manner as to form a spark gap in air with long creepage paths.

The utility of applicant's invention may best be understood by reference to the power distribution art wherein this invention has its widest application. For example, it is common practice to protect distribution transformers from lightning by connecting lightning arresters between the conductors of the transmission line and ground at points adjacent the transformers. These lightning arresters are usually mounted on a cross-arm on a pole or on a bracket attached to the transformer casing, but in either event the lightning arrester must be provided with adequate insulation to prevent a flashover from line to ground. This requires bulky and expensive parts of insulating material and also requires numerous connecting leads which naturally are not only a hazard to the lineman who must work in close proximity to these leads, but are also a potential source of trouble caused by short circuits and grounds. The lightning arresters of the prior art usually comprise a resistance element and one or more series spark gaps all enclosed in an insulating housing. In such enclosed arresters there is a tendency for the spark discharges to cause a deposit of metallic powder on the inner walls of the insulating housing adjacent the gaps and this action combined with the tendency for moisture to collect on these walls tends to permit leakage discharges which cause radio interference or static.

It is an object of the present invention to minimize the above hazards by so mounting a surge diverter of novel construction directly on the apparatus to be protected and adjacent the bushings thereof in such a manner that these bushings insulate the surge diverter.

Another object of this invention is to provide a surge diverter which has a resistance element so mounted adjacent an insulating bushing of the apparatus to be protected that an uninclosed spark gap is formed whereby leakage discharges which cause radio interference are minimized.

Another object of the invention is to provide a surge diverter which is mounted directly on the casing or hangers of the apparatus to be protected and is provided with an arcing element arranged in close proximity with a line conductor

or terminal of the apparatus so as to form a spark gap for the discharge of surge currents.

A further object of the invention is to provide a surge diverter having a novel form of container for a body of material having a negative resistance coefficient with respect to voltage.

A still further object of the invention is to provide a surge diverter which is easily manufactured, is rugged in its construction, and may be readily installed or replaced without the necessity of making connections to high voltage conductors.

These and other objects and advantages are attained by this invention, various novel features of which will be apparent from the description and drawing herein, and will be more particularly pointed out in the claims.

Various illustrative examples of the application of this invention are shown in the accompanying drawing in which:

Fig. 1 is a side view of a surge diverter embodying the invention as applied to electrical apparatus having a terminal supporting bushing, the housing of the surge diverter being shown in section;

Fig. 2 is a top view of the surge diverter shown in Fig. 1;

Fig. 3 is a side view of a transformer installation showing a different way of connecting and mounting a surge diverter embodying the invention;

Fig. 4 is a side view of a surge diverter embodying the invention as applied to an electrical apparatus having a cable extending through an insulating bushing;

Fig. 5 is a side view of a surge diverter embodying the invention as applied to electrical apparatus having a mounting hanger;

Fig. 6 is a top view of Fig. 5 with a portion of the apparatus housing in section;

Fig. 7 is a side view of a surge diverter embodying the invention connected and secured to the bushing supported terminal of electrical apparatus; and

Fig. 8 is a modified surge diverter embodying the invention as applied to electrical apparatus having an insulating bushing.

Referring now more particularly to the drawing, 10 is the metal casing of electrical apparatus such as a transformer, reactor, circuit breaker or the like which is either directly connected to ground or connected thereto through a grounding gap 11. Casing 10 is provided with a hole through which the shank portion of an insulating bushing 12 projects, noting that a gasket 13 is

is interposed between the shoulder of the bushing 12 and the casing 10. Bushing 12 is held in place by means of any suitable clamping device which, for the sake of illustration, is shown as comprising a two part ring 14 and a plurality of circumferentially spaced clamping screws 15. The apparatus (not shown) within casing 10 is adapted to be connected to a transmission line by means of a conductor 16 and a terminal device 18 and lead conductor 17. A protective cap 19 of insulating material such as glass or porcelain is adapted to cover the exposed parts of terminal device 18 and is provided with a slot in one lip through which surge currents may discharge as will be more fully described hereinafter.

The preferred form of surge diverter embodying the present invention comprises a cup-shaped receptacle 21 of insulating material, such as porcelain, which has a hole in the end thereof for the passage of bolt 22, noting that a gasket of material, such as cork, is interposed between the head portion of bolt 22 and the body of the receptacle. An arcing contact finger 24 is secured to receptacle 21 by means of nuts 25, noting that this finger is provided with lip portions 26 which cooperate with raised shoulders on receptacle 21 so as to permit contact finger 24 to be adjusted to a plurality of positions. Receptacle 21 contains a resistance material 27 which has the characteristic of reducing its resistance when the voltage impressed thereon is increased. This material is preferably in the form of one or more cylindrical blocks which contain silicon carbide and graphite. A suitable form of this material is known commercially as Globar. However it is to be understood that other resistance materials known to the art having a valve characteristic may be used, such as granular silicon carbide compounds and oxide pellets for example. When resistance material in the form of blocks is used, the faces of these blocks are preferably provided with metallic coatings produced by electroplating or by the Schoop gun process. Resistance material 27 is held in place in receptacle 21 in electrical contact with bolt 22 by means of any suitable semiplastic compound 28. A conducting base member 29 is held in electrical contact with one end of resistance material 27 by means of bushing cement 31, noting that it is preferable to provide the lip portions of receptacle 21 with sanded surfaces in order that base member 29 may be firmly secured to receptacle 21.

In Fig. 2 base member 29 is shown as provided with a lug portion 32 which has a plurality of mounting holes 33 therein. Mounting holes 33 are utilized to bolt the surge diverter to casing 10 in such a manner that arcing contact finger 24 extends a predetermined distance away from terminal member 18 so as to thereby form a spark gap which is substantially surrounded by air. Inasmuch as arcing contact finger 24 is not connected to line conductor 17, the possibility of leakage currents creeping along solid insulating material and flowing through resistance material 27 to ground is minimized.

In Fig. 3 a transformer is shown connected to transmission line conductors 34 by means of fuse cutouts 35 and lead conductors 17 which are insulated from casing 10 by means of insulating bushings 12. Two surge diverters similar to those shown in Figs. 1 and 2 are mounted on insulating pillars 36 in such a manner that arcing contact fingers 24 form spark gaps with the line terminals as hereinabove described. Base members 31 of the surge diverters are connected to ground by

means of insulated conductors 37. This manner of connecting surge diverters to electrical apparatus is of utility where it is not desired to ground the casing 10. Obviously a grounding gap 11 may be inserted in the ground circuit if desired.

Fig. 4 shows how a surge diverter such as disclosed in connection with Figs. 1 and 2 may be used to protect electrical apparatus of the type having bushings such as shown by 38 through which a flexible insulating cable 39 extends. Rather than remove a portion of the insulation on cable 39, it is preferable to use a pointed screw 41 which pierces the insulation of cable 39 and is held in place by any suitable means, such as threaded member 42 which is mounted in an insulating collar 43 which may be readily slipped over cable 39.

In Figs. 5 and 6 a surge diverter such as disclosed in connection with Figs. 1 and 2 is mounted in close proximity to the terminal member of a transformer by means of a bracket 46 which is bolted to the usual hanger strap 44 which in turn is bolted to a hanger bracket 45 which is preferably welded to casing member 10.

Fig. 7 shows how a surge diverter similar to that disclosed in Figs. 1 and 2 may be supported from the terminal member of an insulating bushing 12. This method of mounting a surge diverter may be accomplished by extending the length of lug portion 32, noting that large hole 33 (Fig. 2) enables this portion to be clamped between the base portion of terminal 18 and bushing 12 with a suitable gasket 30 interposed therebetween. A contact button 48 may be welded or otherwise secured to casing 10 so as to form a spark gap 35 with nut 25 which may be adjusted to vary the length of this gap, or the thickness of gasket 30 may be varied to adjust the length of the spark gap.

In Fig. 8 bushing member 12 is provided with an extra long shaft in order that an annular ring of resistance material 27 may be mounted between casing 10 and the shoulder of said bushing. An arcing contact 51 having one or more arcing points and gasket 13 are interposed between resistance material 27 and the shoulder of bushing 12. In order to exclude moisture from resistance material 27 an insulating tube 21 surrounds material 27 and is sealed by means of compound. A conductive gasket 49 is interposed between the other end of resistance ring 27 and grounded to casing 10.

Although Figs. 3, 4, 5, 7 and 8 show casing member 10 connected directly to ground, it is to be understood that this member may be connected to ground through a grounding gap as shown at 11 in Fig. 1, it being understood that the term grounded casing embraces both of these arrangements.

As to the operation of the surge diverter; upon rise of voltage on conductor lead 17 due to lightning or other surge disturbances the spark gap formed by arcing finger member 24 (or its equivalent) will break down permitting a discharge of surge current through resistance material 27. Inasmuch as this material has a resistance coefficient inversely proportional to the voltage impressed thereon, the surge current will be quickly conducted to ground, however upon cessation of flow of surge current the voltage will drop again to normal and the resistance of element 27 will automatically rise to such a value as to prevent the flow of line current through the surge diverter. Inasmuch as the spark gap in series with the resistance material is external of

the housing member 21 and is unenclosed, there will be substantially no opportunity for leakage currents to flow through the surge diverter in such a manner as to cause radio interference. It is also to be noted that surge diverters embodying the present invention may be applied to electrical apparatus as shown in Figs. 1, 3, 4, 5 and 6 without the necessity of using leads to connect the surge diverter with the line conductor. Certain features of the invention herein disclosed are claimed in my copending application Serial No. 628,876, filed August 15, 1932 for Electrical apparatus.

Although but a few embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. A surge diverter for protecting electrical apparatus which has current conducting means extending through an opening in the housing of said apparatus and is insulated from said housing by an insulating bushing which extends through said opening, said surge diverter comprising in combination, a body of material having a negative resistance coefficient with respect to voltage, means for mounting said body on the exterior of said housing and adjacent said bushing, and means forming a path for conducting currents induced by surge voltages on said current conducting means through said body and said housing, said last mentioned means comprising conductive members having electrical connection with said conducting means and said body respectively forming an unenclosed spark gap in series with said body.

2. A surge diverter for protecting electrical apparatus which has current conducting means extending through an opening in the housing of said apparatus and is insulated from said housing by an insulating bushing which extends through said opening, said surge diverter comprising in combination, a body of material having an inverse resistance characteristic with respect to the voltage impressed thereon, means for mounting said body exteriorly of said housing adjacent said bushing, and means forming a path for conducting currents on said conducting means through said body and through said housing to ground, said last mentioned means comprising metallic members associated with said body forming a spark gap in series with said body and external thereto.

3. A surge diverter for protecting electrical apparatus which has current conducting means extending through the housing of said apparatus and is insulated from said housing by means of an insulating bushing, comprising in combination, a resistance element having an inverse resistance characteristic with respect to voltage supported by said housing adjacent said bushing, and means for establishing a circuit for the flow of surge currents from said current conducting means through said resistance element to said housing upon occurrence of high potential on said conducting means, said circuit establishing means comprising conductive members in electrical connection with said conducting means and said resistance element respectively arranged in spaced relation so as to form a spark gap in

series with said resistance element and external thereto.

4. A surge diverter for protecting electrical apparatus which has current conducting means extending through an opening in the grounded casing of said apparatus and is insulated from said grounded casing by an insulating bushing projecting through said opening, said surge diverter comprising in combination a body of material having an inverse resistance coefficient with respect to the voltage impressed thereon, means for attaching said body to said grounded casing adjacent said bushing so that one end of said body is conductively connected with said grounded casing, a metallic member electrically connected with said current conducting means adjacent said insulating bushing, another metallic member electrically connected with the other end of said body and arranged in spaced relation with said first mentioned metallic member so as to form a spark gap in air between said body and said current conducting means.

5. A surge diverter for protecting a transformer which has a bushing supported terminal connected to a transmission line and has a grounded casing, comprising in combination, a resistance element containing carborundum and having two contact faces, an insulating shell member surrounding said resistance element, a metallic base member attached to said shell member and in electrical contact with one of said contact faces, a contact member mounted on said insulating shell and in electrical connection with the other of said contact faces, and means for attaching said base member to said grounded casing in such position adjacent said bushing that said contact member forms a spark gap with said bushing supported terminal.

6. A surge diverter for protecting electrical apparatus having a terminal supported by an insulator bushing mounted on a grounded housing, comprising in combination, an open ended shell of insulating material, a body of resistance material within said shell having an inverse voltage resistance characteristic, a base member secured to said shell and in electrical contact with one end of said body of resistance material, a contact member secured to said shell and in electrical connection with the other end of said body of resistance material, and means for so securing said base member to said grounded housing adjacent said bushing that a spark gap between said contact member and said terminal is established, said spark gap being of such a length that excessive voltages are discharged across said spark gap through said body of resistance material and through said grounded casing.

7. In combination, a grounded casing, an insulating bushing extending through said casing and having a high voltage terminal, a container of insulating material, a pair of electrodes carried by said container, a body of resistance material within said container and electrically connected across said pair of electrodes, and means for attaching said container to said terminal so that one of said electrodes is electrically connected to said terminal and so that the other electrode is spaced a predetermined distance from said grounded casing thereby forming a spark gap for the discharge of surge currents.

8. In combination, a grounded casing, a high voltage conductor extending through said casing, an insulating bushing arranged to insulate said conductor from said grounded casing, an

75

5
6 arcing contact member secured to said conductor, a surge diverter having an arcing contact finger and a resistance element connected to said finger, and means for attaching said surge diverter to said grounded casing so that said arcing contact finger extends in air in close proximity to said arcing contact member thereby forming a spark gap for the discharge of surge currents.

10 9. In combination, a grounded casing having a hole therein, an insulating bushing extending through the hole in said casing, a high voltage

5
6 terminal carried by said bushing, an annular ring of resistance material surrounding said bushing and having electrical connection with said casing and an annular ring of metal surrounding said bushing and in contact with said resistance material, the said ring of metal being so arranged relative to said high voltage terminal as to provide therewith a spark gap path for the discharge of surge voltages from said terminal through said resistance material to said 10 grounded casing.

LELAND H. HILL.
